United States Patent Office

Des. 229,906
Patented Jan. 15, 1974

229,906

CRIB END

Robert V. Jacobs, Los Angeles, Calif., assignor to
Questor Corporation, Toledo, Ohio

Filed Aug. 3, 1972, Ser. No. 277,809

Term of patent 14 years

Int. Cl. D6—01

U.S. Cl. D6—14

Fig. 1.

Fig. 2.

Fig. 3.

FIG. 1 is a front elevational view of a crib end, showing my new design;

FIG. 2 is a side elevational view; and

FIG. 3 is a top plan view.

The opposite side of the panel shown in FIG. 1 is plain and unornamented.

I claim:

The ornamental design for crib end, as shown.
